(57) **CLAIM**

The ornamental design for guitar rest, as shown and described.

DESCRIPTION

FIG. 1 is a top perspective view of a guitar rest showing my new design;

FIG. 2 is a bottom perspective view thereof;

FIG. 3 is a top plan view thereof;

FIG. 4 is a right side elevational view thereof;

FIG. 5 is a rear elevational view thereof;

FIG. 6 is a front elevational view thereof; and,

FIG. 7 is a bottom plan view thereof.

The left elevational view is an identical, mirror-image of FIG. 4, and is, therefore, not illustrated here.
